UNITED STATES PATENT OFFICE.

LEIGH G. GARNSEY, OF REDLANDS, CALIFORNIA.

RADIATOR SHUTTER.

Application filed April 21, 1926. Serial No. 103,421.

An object of this invention is to provide cheap, simple and effective means for regulating the temperature of internal combustion motors having radiators.

In the invention I provide at one end of the radiator a spring take-up curtain roller with curtain wound thereon, in which the spring brackets of the roller are mounted at one margin of one end of the radiator in such position that when the curtain is drawn out or extended, it will close the ends of cellular openings and obstruct the flow of air through those of the radiator tubes thus covered; and I connect with the bar of the curtain, flexible means leading to position for control by the driver of the engine, so that by drawing the connection the curtain may be adjusted across the open ends of some or all of the radiator cellular openings, and by releasing the connection, the curtain will be rewound on the roller, thus allowing air to flow freely through to cool the radiator more or less, depending on the number of cellular openings left free.

The curtain may be applied at either end of the radiator and the connection which is adjusted may be held in adjusted position by securing it to the dash board or other convenient part of the vehicle within convenient reach of the driver.

In carrying out the invention I have mounted the spring take-up roller at the lower margin of the front end of the radiator and have run the flexible connection from the curtain bar up in front of the radiator and through the upper part of tubes on opposite sides of the top of the radiator, but it is understood that the curtain roller may be journaled at front or back of the radiator and at top, bottom or sides of the radiator as preferred by the constructor.

Further objects of the invention are cheapness, compactness and simplicity of construction, ease of application, and convenience of operation.

Other objects, advantages and features of invention may appear from the accompanying drawing, the subjoined detailed description and the appended claims.

The accompanying drawing illustrates the invention.

Figure 1 is a perspective view of a device embodying my invention applied to the front end of the radiator of an automobile, a fraction of which is shown.

Fig. 2 is an enlarged fragmental detail partly in section.

Fig. 3 is a fragmental detail on a yet larger scale of the parts shown at the lower left corner of Fig. 2. The radiator cellular openings are omitted.

The radiator 1 of an automobile *a* is shown provided on the front end with a curtain 2 mounted on a spring operated take-up roller 3 the ends of which are mounted in brackets 4, 5, which are attached at the side edges of the radiator in such manner that the roller extends across the lower end thereof so that when the curtain 2 is drawn up a greater or less extent it will cover the outer ends of the radiator cellular openings to a greater or less degree as may be desired to restrict the flow of air through the radiator cellular openings.

Guide wires 6 are attached at one end to the base of the brackets 4, 5, and the other ends are attached to the upper end of the radiator, preferably being stretched taut and wound about the outer end of tubes 7 as indicated in Fig. 3.

The curtain is raised or lowered by means of wires, cords or other suitable flexible connection 8 attached at either end of the curtain bar 9, carried through the tubes 7, and to a drum 12 which is in easy reach of and operable by the driver, (not shown).

The tubes 7 are held in place by means of nuts 13 screwed onto the threaded ends of the tubes 7 and the journal brackets 4, 5 are attached by means of bolts 14 inserted through tube 7' and held by nuts 15, and felt and metal washers 16, 17 to protect the surface of the radiator from being marred by the bolts and nuts 14, 15 and brackets 4 and 5.

A housing 18 protects the roller 3 and the curtain rolled thereon and is held in place by the bolts 14 which also attach the brackets 4 and 5 to the radiator.

The outer surface of the curtain is preferably marked as at 19 to simulate the front of the radiator and thereby render it less conspicuous.

I claim:—

1. In combination with an automobile radiator; of tubes disposed in the upper and lower ends of said radiator; bolts extending through the lower of said tubes; brackets secured to the base of said radiator by said

bolts; a rewinding roller journalled in said brackets; a curtain sheet arranged to wind upon said roller and adapted for movement vertically along the front of said radiator; 5 guide means for said curtain and cables connected to the free end portion of said curtain and passing through the upper of said tubes and adapted for actuation to move said curtain.

10 2. In combination with an automobile radiator; of tubes disposed in the upper and lower ends of said radiator; bolts extending through the lowermost tubes; brackets con-

nected to the radiator by said bolts; a rewinding roller journalled in said brackets; 15 a curtain arranged to wind upon said roller and adapted for movement vertically along the front of the radiator; cables connected to the free end of said curtain and adapted for passage through the uppermost tubes and 20 wires connected to said brackets and upper tubes for guiding said curtain.

In testimony whereof, I have hereunto set my hand at Los Angeles, California, this 24th day of March, 1926.

LEIGH G. GARNSEY.
